INVENTOR.
Joseph P. Coulombe

UNITED STATES PATENT OFFICE.

JOSEPH C. COULOMBE, OF KOKOMO, INDIANA.

PRIMING CUP.

Application filed December 29, 1919. Serial No. 348,000.

To all whom it may concern:

Be it known that I, JOSEPH C. COULOMBE, a citizen of the United States, residing at Kokomo, in the county of Howard and State 5 of Indiana, have invented certain new and useful Improvements in Priming Cups, of which the following is a specification.

My invention relates in general to improvements in valves adapted to be used for 10 priming and draining.

It consists in the elements and features of construction shown and described, as indicated in the claims.

The primary object of my invention is to 15 provide a valve that can be used for either priming or draining and which is simple, reliable and economical to manufacture.

A further object of my invention is to 20 provide a valve that has a threaded stem so that it may be pulled to its seat.

A still further object of my invention is to provide a valve that is really self-cleaning, that is that there is no small opening or passage but what is cleaned when the 25 valve is turned.

My invention will be more fully disclosed hereinafter with reference to the accompanying drawing, in which the same is illustrated as embodied in a convenient and 30 practical form and in which;

Fig. 1 is an elevational view partly in section; Fig. 2 is a bottom end view; Fig. 3 is an elevation partly in section of the valve portion itself, showing an optional form of 35 handle; Fig. 4 is an elevation of an optional form of valve portion; Fig. 5 is a partly sectional elevation of a modification of my invention, showing its adaptation as a drain valve for a receptacle.

40 The same reference characters are used to designate the same parts in the several figures of the drawing.

A body —1— has a tapped opening —2— running through it. A rod —3— has a 45 tapered portion —4— which forms the valve and closes opening —2—, having a threaded extension —5— engaging threads in opening —2— to draw it to its seat —6—. The seat —6— is formed by slightly enlarging 50 opening —2—, enough to take out a few threads so as to leave a round hole and left with a sharp corner so that the valve —4— may form its own seat.

The threaded extension —5— is shown

with two flat sides —7— and —8— as I 55 prefer to use this construction as it enables its being made in one operation by a "straddle mill." In Fig. 4 a slot —13— is shown as an optional form of opening to allow the liquid to pass when the valve is 60 open. Fig. 1 shows the valve rod extended and bent to form a handle —9—, while Figs. 3 and 4 show an optional form of handle in the cross-bar —12—. The threaded portion —5— extends through and beyond opening 65 —2— to make self-cleaning possible. In connection with self-cleaning feature, it will be noticed there is but one hole through which the liquid flows through so that it is absolutely self-cleaning. There are many 70 so called "self-cleaning" valves but they invariably have one or more holes that are not self-cleaning.

When desired to be used as a separate unit the body —1— is provided with a male 75 thread —10— adapted to be attached to standard fittings.

When it is desired to use the valve as a priming valve, the body —1— is provided with a cup-shaped portion —11— to facilitate pouring of liquid to the valve.

Fig. 5 is a modification of my invention, with the handle formed from the opposite end of the valve rod, that is the handle —18— is made by extending the threaded 85 stem —17—, instead of extending the valve end —16—. This modification is shown as a drain valve, the body portion —15— is shown soldered to the bottom of a receptacle —14—.

Having described my invention, what I claim is:

1. A priming valve comprising a body having a cup portion, a valve seat at the bottom of said cup portion, a threaded opening below said valve seat, a valve stem for said body having a manual control handle at one end, a threaded portion at the other end, a valve portion formed on said stem intermediate said manual control handle and said threaded portion, said threaded portion having a longitudinal portion cut away to allow the passages of liquid and loosen dirt when said valve stem is turned.

2. A priming valve comprising a body having a cup portion at one end, a threaded opening intermediate said cup portion and the other end of said body, a valve seat in-

intermediate said cup portion and said threaded opening, a valve stem for said body having a control handle at one end, a threaded portion at the other end, a valve portion formed on said valve stem intermediate said control handle and said threaded portion, said threaded portion hav-

ing a longitudinal portion cut away to allow the passage of liquid and loosen dirt when said valve stem is turned.

JOSEPH C. COULOMBE.
